DESIGN FOR A FISHPOND GAME DEVICE

Peter H. Tafelski, Toledo, Ohio

Application April 24, 1944, Serial No. 113,357

Term of patent 7 years

(Cl. D34—5)

To all whom it may concern:

Be it known that I, Peter H. Tafelski, a citizen of the United States, residing at Toledo, in the county of Lucas and State of Ohio, have invented a new, original, and ornamental Design for Fishpond Game Device, of which the following is a specification, reference being had to the accompanying drawing, forming part thereof.

Fig. 1 is a perspective view of a fishpond game, showing my new design.

Fig. 2 is a plan view with the fish shown in Fig. 1 removed.

Fig. 3 is a vertical section on line 3—3 of Fig. 2.

Fig. 4 is a fragmentary detailed view, partly in section, showing one of the fish.

I claim:

The ornamental design for a fishpond game device, as shown.

PETER H. TAFELSKI.
